UNITED STATES PATENT OFFICE

156,023

DESIGN FOR AN AMUSEMENT RIDE CAR

John E. Mitchell, New Brighton, Pa., assignor to
R. E. Chambers Company, Inc., Beaver Falls,
Pa., a corporation of Pennsylvania

Application December 31, 1947, Serial No. 143,467

Term of patent 7 years

(Cl. D34—15)

To all whom it may concern:

Be it known that I, John E. Mitchell, a citizen of the United States, residing at New Brighton, in the county of Beaver and State of Pennsylvania, have invented a new, original, and ornamental Design for Amusement Ride Car, of which the following is a specification, reference being had to the accompanying drawing, forming part thereof.

Fig. 1 is a perspective view showing the front end and a portion of the left side of an amusement ride car, showing my new design, and Fig.

2 a perspective view of the right-hand side of the amusement car.

I claim:

The ornamental design for an amusement ride car, as shown.

JOHN E. MITCHELL.
